MEANS FOR STARTING A DIESEL DRIVEN
LOCOMOTIVE

Frederick F. Murray, Oil City, Pa.

Application May 29, 1931, Serial No. 540,850
18 Claims. (Cl. 60—44)

The present invention relates to the starting up of an internal combustion engine. More particularly, this invention relates to the starting up of an internal combustion engine which is permanently and directly connected to its load. In accordance with the present invention, a Diesel engine or other internal combustion engine may be directly and permanently connected to its load, the starting of the internal combustion engine being brought about without the necessity for disconnecting the engine from its load.

At the present time internal combustion engines, such as Diesel engines, are used to a certain extent for driving ships, locomotives, and so forth, where the load is relatively heavy. Where such engines are thus employed, however, the engines cannot be directly and permanently connected to their load, because no provision has been made for starting the engines under load. Where the load is heavy, as in a case of a locomotive or a ship, it is not practical to transmit the power generated through a clutch, due to the magnitude of the forces involved. Accordingly, it has been necessary to resort to electrical transmissions involving the outlay of considerable capital for the electric current generating mechanism and the motor for driving the load.

In accordance with my invention, I make provision for starting the internal combustion engine by generating fluid pressure at sufficiently high pressure, so that when introduced into the combustion chamber of the internal combustion engine the load may be driven.

Specifically with reference to a Diesel locomotive, I propose to direct connect the prime mover to the wheels without interposing any form of disengaging clutch. Then considering the prime mover cycle of operation to comprise normally the steps of (1) compression, (2) combustion, (3) expansion, I provide broadly in my invention the starting of the prime mover by practicing steps (1) and (2) independently of (3) in a separate apparatus and introducing the products of combustion while under pressure into the prime mover to permit step (3), i. e. expansion, to cause the prime mover to start under load. In the foregoing novel method, step (1) may be practiced either rotatively, i. e. centrifugally in an apparatus separated from the prime mover or it may be practiced by positive displacement apparatus. Step (2) may take place in an especially provided chamber in the case of the centrifugal apparatus or, on the other hand, within the displacement compressor. In each case, proper scavenging is

needed in order to repeat the method for rapid hot fluid pressure generation.

In the following embodiment of my invention, I provide apparatus for generating such fluid pressure by charging a chamber with a combustible mixture and displacing the mixture, the firing of the mixture taking place during the displacement stroke. My invention furthermore provides in combination with an internal combustion engine, apparatus for generating high fluid pressure, the gases being delivered to the combustion chamber of the internal combustion engine while retaining their heat. Furthermore, my invention provides an improved method of starting an internal combustion engine which comprises the steps of igniting a combustible mixture in a compressor chamber and displacing the gaseous combustion products into the combustion chamber of the internal combustion engine while retaining their heat.

In the accompanying drawings in which not as limiting my invention but merely for the purpose of illustrating the same, I have shown one embodiment which the same may assume.

Fig. 1 is a view, principally in central section, of a combustion chamber of an engine to which is connected a compressor for delivering hot gases under high pressure for starting the engine;

Fig. 2 is a sectional view through the valve controlling the intake of the compressor;

ment of parts for the compression and firing of carbureted fuel;

Fig. 11 shows diagrammatically the arrangement of parts for the burning of injected fuel 5 for the compressor of Fig. 6;

Fig. 12 is a diagrammatic plan view showing my invention as embodied in a pair of multiple cylinder units permanently connected to the driving wheels of a locomotive;

10 Fig. 13 is a diagrammatic perspective view of the cams controlling the inlet and discharge valves for the compressor connected with a pair of cylinders as shown in Figs. 7 and 8; and

15 Fig. 14 is a sectional view in a different plane from Fig. 6 illustrating the inlet and discharge passages of the compressor shown in Fig. 6.

This application is a continuation in part of 15 my copending applications Ser. No. 57,096, filed Sept. 18, 1925, and Ser. No. 258,541, filed Mar. 2, 20 1928.

The engine selected for illustration is of the Diesel type, and comprises a cylinder 6 provided with exhaust ports 7 and inlet ports 7a. Within the cylinder is reciprocable a piston 8 connected by a connecting rod 9 to a crank shaft 10. But one cylinder of the engine is shown in Fig. 1, it being understood that a plurality of cylinders will be provided as shown in Figs. 7 and 12. The mechanism for injecting fuel into the cylinder 6 is not shown in detail, since various mechanisms suitable for this purpose are well known in the art.

My invention relates broadly to the starting up of an internal combustion engine whose load is permanently connected to the crank shaft, and must, therefore, be driven during the starting of the engine. The entire load which is driven by the internal combustion engine, such as a Diesel engine, when the latter is operating under its own power, must be set in motion and driven while the internal combustion engine is being started. I have solved this difficult problem by introducing into the cylinder 6 fluid at high pressure, this fluid pressure being generated in a compressor having novel features permitting the generation of the high pressure and large volume required under the circumstances.

Stated simply, the principle of operation of my improved compressor involves the burning 50 of a charge of fuel in a combustion supporting medium within the compressor cylinder, and reciprocating the piston of the compressor so as to displace the gaseous products of combustion into the cylinder 6. The combustion of the fuel gives rise to a large volume of gaseous combustion products at a high temperature. In order 55 to maintain the necessary high pressure which is required in order to start the Diesel engine under load, I connect a prime mover to the crank shaft of the compressor so as to displace the gaseous products of combustion from within the compressor cylinder by power derived from an independent prime mover. The compressor will now be described more in detail.

60 Closely adjacent the cylinder 6 is disposed a compressor cylinder 12 within which is reciprocable a piston 13. The crank shaft 14 of the compressor is driven by suitable driving connections 15 from a prime mover 16. The prime mover 16 may be of any suitable type, but must be powerful enough to force the piston 13 toward the end of the cylinder 12 and displace the gaseous combustion products even when this discharge takes place against high back pressure.

75 It will be noted that no receiver is provided be-

tween the cylinder 12 and the cylinder 6; and accordingly a high pressure is built up within the cylinder 6 so rapidly as to produce within the cylinder the required pressure after but a few strokes of the piston 13 at the most. The gaseous products of combustion above mentioned must be displaced from the cylinder 12 against such back pressure; and accordingly, the cross sectional area of the piston 13 must be so related to the power of the prime mover 16 that this prime mover will be successful in driving the compressor. A fly wheel 17 on the crank shaft 14 promotes the smooth running of the compressor.

The gaseous products of combustion are conducted as directly as possible from the head 18 of the compressor to the head 19 of the internal combustion engine. These gases are at such high temperature that heat resisting alloys are preferably employed in the construction of the heads 18 and 19. Such alloys are well known in the metallurgical art and need not be referred to in detail in this application.

In order to cut down the clearance volumes of the cylinders 6 and 12, a check valve is arranged at each end of the passageway 23 leading from the cylinder 12 to the cylinder 6. The check valve 20 is spring pressed against a seat 21 in the head 18. In similar fashion a spring pressed valve 22 controls the discharge end of the passageway 23. The valves 20 and 22 are subjected to high temperature conditions and are preferably formed of a heat resisting alloy; and these valves may, within the contemplation of my invention, be water cooled. Passages 24 are formed within the heads 18 and 19 for the circulation of cooling fluid to prevent the destruction of these heads by the high temperatures occurring within the cylinders.

The introduction of fuel and the burning of the same within the cylinder 12 is controlled 40 jointly by the crank shaft 10 of the internal combustion engine and the crank shaft 14 of the compressor. It is within the contemplation of my invention that fuel in liquid, solid or in carbureted form may be charged into the cylinder 12. If liquid or solid fuel is injected, it may be ignited by the compression within the cylinder 12. Preferably, however, the liquid or solid fuel is ignited at the time it is injected into the cylinder. In any event, the ignition of the charge 45 of fuel should take place substantially before the displacement stroke of the piston 13 is completed.

55 My improved compressor may be operated with carbureted fuel, Fig. 1 showing an arrangement for burning carbureted fuel, or with liquid or solid fuel, Fig. 6 showing an arrangement for burning the latter type of fuel. In Fig. 1 a conduit 30 leads from a suitable carburetor to an inlet passage 31 in the head 18; and a valve 32 controls the port through which the charge of fuel is admitted to the cylinder 12. Although a check valve may be employed at this point, I prefer to employ a mechanically actuated valve. 60 As shown more particularly in Fig. 2, the valve 32 is pressed outwardly by a compression spring 33, acting against a washer or flange 34 on the valve 32. During the return stroke of the piston 13, a combustible charge is drawn into the cylinder 70 12, the valve 32 being opened to permit the admission of the charge. During the displacement stroke of the piston 13, the charge is fired by a spark plug or other suitable ignition device 35 projecting within the cylinder 12 adjacent its 75

end. The firing of the charge within the cylinder 12 is timed from the crank shaft 14 by mechanism later to be described. At the end of the displacement stroke of the piston 13, the clearance space at the end of the cylinder 12 is vented to atmosphere by means of a vent valve 37 controlling a passageway extending longitudinally of the valve 32. The clearance space at the end of the cylinder 12 is made as small as possible to avoid the re-expansion of burned gases within the cylinder 12. The opening of the valve 37 discharges to atmosphere the pressure remaining within this small clearance space along the passageway within the valve 32, the stem of the valve 37 being fluted to permit flow of the burned gases along the same. The valve 37 is pressed by a spring 38 toward a seat 39 formed on the valve 32 surrounding the passageway which extends through the valve 32 as above mentioned; and the spring 38 is under compression between the washer or flange 34 and the head 39^a of the stem of valve 37.

Valve actuating mechanism is provided for controlling the valves 32 and 37. The end of a lever 40 is arranged to cooperate with the head 39^a so as to open the valves 32 and 37 at the proper time. The lever 40 is pivoted to a standard 41 on the head 18, and is connected by a link 42 to a rod 43. It will be understood that the rod 43 is disposed adjacent the cylinder 12, this rod being shown more or less diagrammatically in Fig. 1, so as to clarify the principle of operation of the mechanism. The rod 43 carries a washer 44 against which bears one end of a coil spring 45, the other end of the spring 45 bearing against a support 46. The spring 45 tends to move the rod 43 to the left so as to bring a cam roller 48 rotatably carried by the rod 43 into operative relation with a cam 49 secured to a cam shaft 50. A helical gear 51 on the shaft 50 meshes with a helical gear 52 carried by a shaft 53. This shaft extends adjacent the crank shaft 14 and carries a helical gear 54 meshing with a helical gear 55 secured to the crank shaft 14. The helical gear 55 is so proportioned that the shaft 50 is driven at the same speed as the crank shaft 14; and, therefore, the cam 49 rotates in synchronism with the reciprocation of the piston 13. When the rod 43 is moved to the left so that the roller 48 is in operative relation to the cam 49, the lever 40 is rocked to permit the admission of a charge of carbureted fuel to the cylinder 12. The cam 49 is so positioned on the shaft 50 that the lever 40 starts to depress the head 39^a at substantially the end of the compression stroke of the piston 13. The spring 33 maintains the valve 32 closed, but the valve 37 is opened so as to scavenge the clearance space at the end of cylinder 12. Further movement of the link 42 causes the lever 40 to move the head 39^a far enough so that the bevelled faces 57 engage the cup shaped surface 58 within the upper end of the stem of the valve 32. This prevents the flow of gases through the passageway in the valve 32; and simultaneously the valve 32 starts to open. Carbureted fuel accordingly enters the cylinder 12 during the downward stroke of the piston 13. Near the end of this stroke the cam 49 moves out from beneath the roller 48; and the lever 40 is rocked so as to close both the valve 32 and the valve 37. The direction of movement of the piston 13 is now reversed and compression of the charge followed by ignition of the same takes place.

The delivery of carbureted fuel to the cylinder 12 should be interrupted during the return stroke

of the piston 8 so that no discharge of pressure fluid shall take place into the cylinder 6 during the movement of the piston 8 toward the head 19. I have provided a cam controlling mechanism which moves the roller 48 out of operative relation during this stroke of the piston 8. The rod 43 carries on the other end from the roller 48 a roller 60 which is caused to ride against the surface of a cam 61 by the spring 45. The cam 61 is secured to a shaft 62 carrying a helical gear 63. This gear meshes with a helical gear 64 on a shaft 65 driven through gearing 66 from the crank shaft 10 of the internal combustion engine. The gearing 63, 64 and 66 is so proportioned that the shaft 62 is rotated at the same angular rate as the crank shaft 10. Accordingly, the cam 61 is rotated in synchronism with the reciprocation of the piston 8. During the upward stroke of the piston 8 the roller 60 is riding on the high portion of the cam 61, and the roller 48 is moved to the right so as not to be in contact with the cam 49. Accordingly, the inlet valve 32 remains seated, and no carbureted fuel is admitted to the cylinder 12. Since the clearance space at the end of cylinder 12 is the smallest possible, it is undesirable to reciprocate the piston 13 without relieving this clearance space, as otherwise the number of compressions would be too high for safety. Accordingly, I provide a cam bracket 68 mounted on a support extending from the cylinder block 30 in such position as to lift the rod 42 and depress the valve 37 off its seat, when the cam 61 is in the position shown in Fig. 1. The bracket 68 is provided with a cam surface 69 onto which the roller 48 may roll when the rod 43 is pushed to the right by the cam 61.

In order that the valve 37 may be manually lifted off its seat to relieve the end of the compressor cylinder, either when the compressor is being started or at some other time when it is desirable to prevent excessive pressure, I provide a lever 70 connected by a link 71 with the link 42. An eye 72 on the end of the link 71 surrounds the link 42, so as not to interfere with reciprocation of the link 42. A ratchet segment 73 is provided for holding the lever 70 in position for disengaging the cam roller 48 from the cam 49. During normal operation of the valve 32, a link 74 holds the ratchet 75 away from the segment 73 so that the lever 70 is free to oscillate as the cam 61 moves the rod 43 back and forth. During the stroke of the piston 8 away from the head 19, the roller 60 is riding on the low surface of the cam 61, and the valves 32 and 37 are so actuated that fuel is delivered to the cylinder 12 to be ignited and displaced therefrom into the cylinder 6. It will be noted, therefore, that the compressor is controlled so that displacement of gaseous combustion products takes place from the cylinder 12 into the cylinder 6 only so long as the piston 8 is being forced away from the head 19 of the engine.

The ignition of the fuel takes place substantially before the displacement stroke of the piston is completed. I have found that a suitable time for the ignition of the charge being compressed in the cylinder 12 is when the crank is moving toward dead center and is approximately 45° away from dead center. I have shown in Fig. 9 one form of a timing device which may be employed for igniting the charge of fuel. It will be understood, however, that this showing is merely conventional and that various types of timers are well known, and that accordingly any suitable

type of timer may be substituted for the one shown.

In the form of timer shown in Fig. 9, a low voltage battery supplies current through a wire 76 to both a primary winding 76^a and a secondary winding 77. The primary winding (low tension) consists of a few turns of fairly heavy wire around an iron core 78. The secondary winding consists of a large number of turns of fine wire wound over the primary winding. The battery current flowing through the primary coil and grounded at 80 is made and broken at contacts 81, one of these contacts being on the end of a pivoted lever 82. A cam 83 driven at the same angular rate as the crank shaft 14 is arranged to rock the lever 82 so as to open and close the contact at 81. In the embodiment shown, the cam 83 may be on the crank shaft 14 or on a shaft driven from the crank shaft 14 at the same angular rate. A condenser 84 is provided to prevent arcing at the contacts 81.

As shown in Fig. 9, the cam 83 is in the position which corresponds to the position of the piston 13 shown in Fig. 1. Since the cam is rotated in a counter-clockwise direction, it will be apparent that the contacts 81 will open to break the circuit through the primary winding at about the time the crank shaft 14 is 45° from the dead center position shown in Fig. 1; and accordingly, the ignition of the charge will take place approximately at the time the crank is 45° from dead center.

In order to make certain that there shall be no ignition of a charge at the time that the piston 8 is moving upwardly in the cylinder 6, I have provided a device for grounding the circuit to the spark plug 35 when the roller 60 is on the high part of the cam 61. This device comprises a bracket 85 secured to the rod 43. A contact 86 carried by the bracket 85 is grounded through a wire 87. A wire 88 connected to the circuit to the spark plug 35 is connected to a contact 89 supported in position to be engaged by the contact 86 when the rod 43 is moved to the right into the position shown in Fig. 1. It is apparent, therefore, that when the high portion of the cam 61 moves the rod 43 to the right, the circuit to the spark plug 35 will be grounded and no ignition of the charge by the spark plug 35 will take place.

In Fig. 4 I have shown a safety device for preventing the building up of too high a pressure in the passageway 23. A conduit 90 leads to a diaphragm 91 having a yieldable plunger 92 which is grounded as shown at 93. The plunger 92 is arranged so that when it is extended by excessive pressure acting against the diaphragm 91, a wire 94 connected to the spark plug 35 is grounded through a contact 95. Accordingly, when excessive pressure occurs in the passageway 23, the spark plug 35 is grounded so that no ignition of a charge in the compressor may take place.

In Fig. 5 I have shown a modified form of compressor in which the discharge valve is mechanically operated. The piston 13 is shown at the end of its compression stroke and the cam 49 has lifted the roller 48 just sufficiently to open the bleeder valve 37. In dotted lines is shown the position the roller 48 will assume when moved to the right by the cam 61, this movement taking place whenever the piston 8 is rising in the cylinder 6. The shaft 50 carries, in addition to the cam 49, a smaller cam 96 with which engages a cam roller 96^a carried by a rod 97. A lever 97^a

guided by an upright 97^b on the head 18 is actuated by the rod 97 so as to move the stem 98^a of a valve 98 toward and from its seat 21. A set of springs 99 is housed within a casing 99^a, these springs being of sufficient strength to maintain the valve 98 closed during the compression of the air or other combustion supporting medium in the cylinder 12 by the piston 13.

The cam 96 is so shaped and so positioned on the shaft 50 that the lever 97^a is rocked to open the valve 98 upon ignition of the charge of fuel. At the end of the compression stroke, this being the position shown in Fig. 5, the cam 96 permits closing of the valve 98 by its spring mechanism 99. The spring mechanism 99 is shown as a double spring, since a heavy spring pressure is desirable. The rod 43 is shown in Fig. 5 as moving back and forth under the control of cam 61 to periodically move the roller 48 to a position in which it is not engageable by the high portion of cam 49. The cam roller 96^a which cooperates with cam 96 may or may not be removed from operative relation with the cam 96, in accordance with whether or not it is desired to maintain the valve 98 closed during the up stroke of piston 8. In case it is desired to maintain the valve 98 closed during the up stroke of piston 8, a second cam, shaped like the cam 61, is secured to the shaft 62 and on the same side of shaft 62. This second cam cooperates with a roller and rod, such as the roller 60 and rod 43 to periodically move the roller 96^a to inoperative position. No cam bracket is required to cooperate with the roller 96^a since it is not intended that the valve shall be opened during the up stroke of piston 13.

In Fig. 5 a different type of manual control for the rod 42 is provided from the one shown in Fig. 1. The lever 70^a is a bell-crank lever having a latch 75^a cooperating with a segment 73^a. The link 71^a is connected by a pin and slot connection 72^b to the bell-crank lever 70^a. Due to the lost motion connection thus provided, the lever 70^a may be released and kept in released position.

As previously mentioned, and as shown diagrammatically in Figs. 10, 11 and 14, carbureted fuel (Figs. 1 and 10) may be supplied to the cylinder 12; or, as shown in Figs. 6 and 11, liquid or solid fuel may be injected and ignited. In Fig. 6 I have shown a cylinder 100 within which reciprocates a piston 101 actuated by a crank shaft 102. Air from any convenient source of supply, as for instance, by the suction of the receding piston 101, or preferably under pressure, is supplied to the cylinder 100 through air inlet passage 103 (see Figs. 11 and 14). The admission of the air may be controlled by an air inlet valve seated by a light spring. Air is thus admitted automatically upon the downward movement of the piston 101, the inlet valve closing on the compression stroke of the piston.

The discharge outlet 104 is connected through passage 23 to the combustion chamber of the internal combustion engine which is permanently connected to its load.

The operating cycle of the explosive compressor is as follows:—The crank shaft 102 is rotated by an outside power source such as the engine 16 shown in Fig. 3. Starting air pressure, scavenging and supercharging air pressure are supplied by small auxiliary air compressor sets. As these auxiliary units are well known in the art, they are not shown in the drawings.

As the piston 101 starts downwardly, scavenging and supercharging air under pressure enter

the cylinder 100 by way of the intake 103 past the inlet valve.

When the piston is in its lowermost position, the scavenging ports 105, which open through the cylinder walls, are uncovered by the piston so that any burned gases from previous combustion are in this way cleared from the cylinder. As the piston rises on its compression stroke, these ports are closed, the air pressure above the piston quickly rising above that of the scavenging and supercharging air pressure so that the inlet valve closes. The discharge valve, which may be of the type shown in Fig. 1, but preferably of the mechanically operated type shown in Fig. 5, prevents discharge from the cylinder 100 during the compression of the combustion supporting medium.

At the proper instant in the compression stroke of the piston 101, after the heat of compression in the cylinder becomes sufficient to ignite a fuel, fuel is injected into the cylinder 100 above the piston. Preferably, the injection is timed to take place at such an interval prior to the completion of the up stroke of the piston 101 that the crank shaft 102 is at an angle of 45° from the dead center position shown in Fig. 6. The fuel ignites due to heat of compression or, in the case of some fuels, may be fired by some hot bulb or sparking device of which a variety of types are well known. Due to this ignition, the pressure of the resultant gases of combustion rises. At the same time the piston is moving on its compression stroke, thus augmenting the pressure generated by the burning of the fuel. The outlet valve opens and the burned gases, together with the still burning fuel and the air remaining in the cylinder, are expelled from the cylinder as the piston completes its upward stroke.

In order to control the timing of the fuel injection, I provide regulating mechanism as shown in Fig. 6. From the pump 107 leads a fuel supply pipe 108. When the bleeder 110 is unscrewed, oil is permitted to make its way out of the bleeder passage 111 should the pump 107 be operated. When starting, the pump 107 is operated manually to free the oil pipe 108 of air. The bleeder 110 is then screwed down to prevent any further discharge of oil by way of passage 111, the oil thereafter passing down through the conduit 112. A valve 113 controls the admission of fuel to the cylinder 100, this valve being provided with a fluted stem 114 which carries a closing spring 115.

When the fuel oil is delivered into the cylinder 100, the pump 107 drives the oil under pressure through the pipe 108 and along the flutes of the valve stem 114 within the conduit or passageway, the valve 113 being finally moved off its seat against action of the closing spring 115 and against the compression pressure entering the diffusing holes 116 from the cylinder. It is to be borne in mind that fuel is fed into the cylinder during the up or compression stroke of the piston 101. Upon cessation of adequate pressure in the pipe 108 to open the valve 113, the valve is closed by this spring.

For operation of the fuel pump 107, I provide a gear 118 rotating with the crank shaft 102 which drives the piston 101. The gear 118 drives a helical gear 119 mounted on a shaft 120 which also carries a similar gear 121. A gear 121 drives a gear 122 meshing with a gear 123, which latter gear drives a rotating pin 124. Connecting rod 125 attached to the pin 124 carries a roller 126 which is caused to reciprocate vertically by

reason of a link 127 connected at one end to the roller and pivoted at its other end to a support 128. Rotation of the crank shaft 102, therefore, not only causes reciprocation of the piston 101 but also reciprocates the roller 126.

The oil pump is of the plunger type and its plunger 129 is caused to move upwardly by a spring 130. The upper end of the plunger is provided with a cap 131 adapted to engage an upper limit stop 132. The pump suction valve 133 operates with the inlet to the pump chamber and the check valves 134 control discharge from the pump chamber.

On the upward stroke of the pump plunger 129, oil from a supply tank is drawn through pipe 135 into the space 136 within the pump, and past the suction valve 133 into the plunger space 137 of the pump. On the downward stroke of the plunger under the action of the pin 124, rod 125 and roller 126, fuel will be discharged from the delivery space 137 past the valves 134 into the fuel pipe 108.

The commencement of the down stroke of the pump plunger 129 is determined by the position of the explosive compressor piston 101 in its cylinder on its up stroke. The timing of fuel ignition about to be described, is accomplished by means of cam 141 attached in any desired position on the same shaft as gear 122. The gear 123 is placed in mesh with gear 122 in such relation as to insure that the plunger 129 moves on its displacement stroke as described during such a length of time as fuel injection is desired. The specific timing of injection of the fuel into the cylinder 100 is brought about as follows:—The timing cam 141 is driven in a clockwise direction by the gear 122. A cam follower 142 attached to one arm of a bell-crank 143 operates with the cam 141. A rigid connecting rod 144 is attached to the other arm of the bell-crank lever 143 and pivotally connected to this rod is a lever 145 fulcrumed at 146. A push rod 147 is (with the parts as shown in Fig. 6) held in contact with the lever 145 by a spring 148, the push rod extending into the space 136 of the oil pump in such position as to contact with the pump suction valve 133 above referred to. When fuel delivery through pipe 108 takes place, the upper end of the rod 147 is just short of contact with the suction valve 133.

Again referring to the timing cam 141, it will be seen that when the follower 142 engages the recessed portion of the cam, the rod 145 will have moved (if necessary, along the slot 150) to position to permit the spring 148 to move the push rod 147 away from the valve stem to permit the pump plunger 129, which is moving downwardly, to close this valve and discharge fuel oil through the check valves 134 into the compressor cylinder 100. On the other hand, when the plunger 129 is in the position shown in the drawings with the cam follower 142 in the position shown, the suction valve 133 will be held open so that a downward movement of the oil pump plunger at that time will merely force fuel past the valve 133 into the space 136 until such time as the suction valve 133 is released by the push rod 147. Specific timing, therefore, of fuel injection past the injection valve with respect to the movement of compressor piston 101 is afforded by the cam 141, follower 142 and associated mechanism. While the instant of injection of the fuel into the cylinder 100 on the explosive compressor may be varied as desired, fuel injection commences, as shown in Fig. 6, approximately at mid-compression

stroke of the compressor piston 101, at which time the cam 141 is turned so that the point 151 of the depression therein is under the follower 142 which corresponds to the fuel pump actuating pin 124 being at the point 138. Injection of the fuel, therefore, would continue while the cam 141 is turning clockwise from the assumed position (point 151 under cam follower 142) until the other end 152 of the cam depression moves beneath the cam follower to interrupt the pumping of the fuel already described.

The timing mechanism already described provides for injection at the proper time of fuel into the cylinder 100 on the compression stroke of the piston. It is desirable that the injection of fuel be discontinued during the upward stroke of the piston 8 of the internal combustion engine. To this end, therefore, I mount a cam 154 on a shaft 155 driven in similar fashion as in the mechanism shown in Fig. 1 from the crank shaft 10. As previously explained, 155 rotates in synchronism with the crank shaft 10. A cam follower 156 rides on the surface of the cam and through a bell crank 157 and link 158, which is connected to the bell crank 143, and raises and lowers the lever 145. With the parts in the position shown in Fig. 6, the piston 8 is rising and the lever 145 is lifted to prevent the discharge of fuel through the pipe 108. As soon as the piston 8 starts on its down stroke, the cam follower 156 rides off the high portion of the cam 154; and discharge of fuel through the pipe 108 is again permitted by lowering of the lever 145, should the cam 141 be in the proper position.

It is furthermore desirable that the fluid pressure supplied by the explosive compressor to the cylinder of the internal combustion engine shall not exceed a predetermined pressure. To this end, therefore, I provide a pressure governing diaphragm of the type shown in detail in Fig. 4 connected by a pipe 90 to the passageway 23 shown in Fig. 1. The plunger 92 of the diaphragm is in alignment with the push rod 147. Should the predetermined pressure be exceeded, the push rod 147 will hold the valve 133 off its seat, irrespective of the position of the lever 145, the slot 150 permitting relative movement between the lever 145 and the push rod. So long as the excessive pressure continues, therefore, the plunger 92 will prevent the discharge of fuel through the pipe 108 into the cylinder 100.

In Figs. 7 and 8 is shown an arrangement in which a compressor cylinder is connected with two cylinders of an internal combustion engine. The water jacketed cylinders 6^a and 6^b are connected by water cooled passages 160 and 160' to the compressor cylinder 12^a. Valve mechanism for controlling the supply of fuel to the cylinder 12^a and the discharge of the products of combustion from the cylinder 12^a into the cylinder 6^b is shown diagrammatically in Fig. 8, the cams for controlling these valves being shown in Fig. 13. A spring loaded inlet valve 161 is controlled by cam operated lever mechanism 162 of the type shown in Figs. 1 and 5. A discharge valve 163 is controlled by cam operated lever mechanism 164 of the type shown in Fig. 5. A check valve 165 permits the discharge of the products of combustion into the cylinder 6^b.

It will be understood that since two mechanisms 164 are provided, two cams 96 and 96^b must be provided on the shaft 50. These cams will, as shown in Fig. 13, be arranged to project from the same side of the shaft 50. It will be understood that the pistons in the two cylinders 6^a

and 6^b will not be rising at the same time. Accordingly, the cams 61 and 61^a will be positioned on different sides of the shaft 62. If the cranks of the pistons in the cylinders 6^a and 6^b are 180° apart, the cams 61 and 61^a will be correspondingly oriented on the shaft 62, as shown. It should be borne in mind that the shaft 50 may revolve a considerable number of times for each revolution of the shaft 62, since the shaft 50 revolves at the same angular rate as the crank shaft of the explosive compressor. So long as the roller 60 engages the low portion of the cam 61, the lever mechanism 164 operated thereby functions to admit explosive charges of fuel into the cylinder 12^a, the cam 96 opening the valve 61 each time the piston is moved downwardly in the cylinder 12^a. The cam roller 96^c will be held in inoperative position so long as the roller 60^a engages the high portion of the cam 61^a, and accordingly, the cam 96^b is ineffective to open the discharge valve controlled thereby. Since the discharge is taking place from the compressor continuously to either cylinder 6^a or cylinder 6^b, there is no need for rendering the inlet valve inoperative as in the form shown in Fig. 1. Accordingly, the cam 49 cooperates with the roller 48 to open and close the inlet valve on the downward and upward strokes of the piston in the cylinder 12^a.

Although I have shown diagrammatically an arrangement for starting up a two-cylinder internal combustion engine, the explosive compressor comprising but a single cylinder, it will be understood that I contemplate the use of a plurality of cylinders in the internal combustion engine and the connection thereto of a plurality of cylinders in the explosive compressor, as shown in Fig. 12. The cam mechanism and valve mechanism for controlling the discharge of high pressure fluid from the explosive compressor into the cylinders of the engine will be constructed in accordance with the principles disclosed in Figs. 7, 8 and 13 and set forth in the above description.

In Fig. 12 I have shown my invention embodied in a locomotive having a pair of Diesel engines 202 permanently connected to the driving wheels. As shown, there are six pairs of driving wheels 200. These wheels are being connected by links 201 in two sets of six wheels each, or they may all be connected together by conventional side rods. A Diesel engine 202 is connected by beveled gearing 203 to a shaft 204 rotatable in bearings 205. A gear 206 is secured on each end of the shaft 204, and meshes with a gear (not shown as it is immediately below the gear 206) secured to the driving wheel 200. In similar fashion, the Diesel engine unit 210 is connected by beveled gearing 211 to gears 212 on a shaft 213 so as to drive the second set of wheels. With each of the Diesel engine units cooperates an explosive compressor 215 actuated by a prime mover 216. When starting up the locomotive, the prime movers 216 are started so as to drive the crank shafts of the compressors 215. The levers 70 (or 70^a, as the case may be) are next released so that fuel is admitted to the cylinders of the explosive compressor. The prime movers 216 drive the crank shafts of the explosive compressors so as to displace the products of combustion successively into the cylinders of the Diesel engine unit. Due to the high pressure of the gaseous products of combustion thus afforded into a cylinder of each of the Diesel engine units, the wheels 200 are driven to start the locomotive.

When the locomotive has attained sufficient

speed, as for instance, $\frac{1}{16}$ to $\frac{1}{8}$ of maximum speed, the explosive compressors are shut off, and the Diesel, which is already in a running condition due to the high temperature of the gases used to start the same, is started functioning on its own cycle.

It will be apparent that I have provided an improved arrangement for connecting an internal combustion engine directly and permanently to its load. As an important feature in solving the problem of starting up such an engine, I have devised an improved method of generating high fluid pressure in which the pressure generated by burning fuel in a combustion supporting medium is not dissipated but is fully applied to the piston or pistons of the internal combustion engine to start the same under load. It will, furthermore, be apparent that in accordance with my improved method of starting an internal combustion engine, a charge of fuel, together with a combustion supporting medium, are mixed and burned in one cylinder and are thereupon transferred by power derived from an outside source to the cylinder of the internal combustion engine to there perform useful work.

My invention has the distinct advantage that, as shown in Fig. 12, the wheels of a locomotive may be directly and permanently connected to one or more Diesel engines. My invention provides for starting up the Diesel engine or engines thus connected, and then changing over to the regular Diesel cycle when the locomotive has attained sufficient speed. It is noteworthy that the Diesel engine which is started in this manner is already in a running condition when it is started functioning on its own cycle, since the gases which are supplied by my improved explosive compressor to the Diesel engine are at a high temperature and heat the walls of the cylinders of the Diesel engine.

While I have illustrated and described several specific forms of explosive compressor and several arrangements for connecting one or more explosive compressors with a cylinder or cylinders of an internal combustion engine, it will be understood that the invention is not restricted to the particular constructions and arrangements shown, but may be variously modified within the contemplation of the invention and under the scope of the following claims.

I claim:

1. In combination, an internal combustion engine permanently connected to its load, and means for supplying gaseous combustion products at high temperature and under high pressure to said engine to start the same under its load comprising a combustion chamber, a displacement member reciprocable in said chamber, means for supplying fuel and medium capable of supporting combustion to said chamber, means for delivering gaseous products of combustion directly from said chamber to said internal combustion engine, and a prime mover for moving said displacement member against the pressure generated by such combustion in said combustion chamber to expel the gaseous products of combustion under such generated pressure.

2. A motor comprising in combination a cylinder and piston, and apparatus for supplying actuating fluid to the same comprising a combustion cylinder, means for supplying a combustion supporting medium to said combustion cylinder, a piston reciprocable in said combustion cylinder, means for injecting fuel for combustion in said medium, means for conducting the gaseous prod-

ucts of combustion directly from said combustion cylinder to the first-mentioned cylinder and a prime mover for moving said second-mentioned piston against the pressure generated by such combustion in said combustion cylinder to expel the gaseous products of combustion under such generated pressure from the combustion cylinder into the first-mentioned cylinder.

3. In combination, an internal combustion engine, and an explosive compressor for supplying gaseous products of combustion to said engine under high pressure to start the same, said explosive compressor comprising a combustion cylinder, means for supplying a charge of medium capable of supporting combustion and fuel to said cylinder and for burning and substantially completely displacing said charge from said cylinder, said means comprising a piston reciprocable within said cylinder with minimum clearance space at the end of the displacement stroke, and means for actuating said piston, said actuating means being driven independently of the power generated by such combustion within said chamber for moving said piston against the pressure generated by such combustion to displace substantially all the gaseous products of combustion from the compressor cylinder.

4. In a locomotive, a driving wheel for engaging the track, an internal combustion engine for furnishing power to the driving wheel, and means for supplying fluid at high temperature and under high pressure to the internal combustion engine to start the locomotive comprising a combustion chamber, means for supplying fuel and medium capable of supporting combustion to said chamber, a displacement member reciprocable within said chamber, means for conducting the gaseous products of combustion directly from said combustion chamber to the internal combustion engine, and a prime mover for reciprocating said displacement member against the pressure generated by such combustion in said combustion chamber.

5. In combination, in a locomotive, a driving wheel, an internal combustion engine permanently connected to said wheel to drive the same, and an explosive compressor discharging directly into said internal combustion engine for supplying pressure fluid thereto to start the locomotive, said explosive compressor comprising a combustion chamber, means for supplying fuel and medium capable of supporting combustion to said combustion chamber, a displacement member reciprocable in said combustion chamber, means for conducting gaseous products of combustion directly from said combustion chamber to said internal combustion engine and a prime mover for actuating said displacement member against the pressure generated by such combustion to expel the gaseous products of combustion under such generated pressure from said combustion chamber into said internal combustion engine.

6. In combination, in a locomotive, a driving wheel, an internal combustion engine permanently connected to said wheel to drive the same, an explosive compressor for supplying pressure fluid for starting the locomotive, and a prime mover for driving said compressor, said compressor comprising a combustion cylinder, means for supplying fuel and a medium capable of supporting combustion to the combustion cylinder, and means for burning the mixture and expelling the gaseous products of combustion from said combustion cylinder into said internal combustion engine, said last mentioned means includ-

ing a piston reciprocable within said cylinder by said prime mover against the pressure of combustion.

7. Apparatus for generating high fluid pressure comprising a combustion cylinder, means for charging said cylinder with fuel and medium capable of supporting combustion, means for burning the charge and expelling the gaseous products of combustion from the cylinder comprising a piston and actuating mechanism for reciprocating said piston within the cylinder against the pressure of combustion, and valve mechanism operated in timed relation with the reciprocation of said piston for controlling the discharge of said gaseous products of combustion.
8. A compressor for generating high fluid pressure comprising a compressor cylinder, means for charging said cylinder with fuel and medium capable of supporting combustion, means for burning the charge and expelling the gaseous products of combustion from the cylinder comprising means for firing the charge, a piston reciprocable within the compressor cylinder, means for actuating said piston against the pressure of combustion, valve mechanism for controlling the discharge of said gaseous products of combustion from the cylinder, and timing means for causing said valve mechanism and firing means to be operated on the compressing stroke of said piston.
9. A motor comprising in combination a cylinder and piston, and means for supplying actuating fluid to the same comprising a combustion cylinder, means for supplying medium capable of supporting combustion to said combustion cylinder, a piston reciprocable in said combustion cylinder, means for injecting fuel for combustion in said medium, means for conducting products of combustion directly from said combustion cylinder to the first mentioned cylinder, actuating means for said second mentioned piston driven independently of the power generated by such combustion within said combustion cylinder, and timing means for causing ignition of said mixture during the compressing stroke of its respective piston and for causing displacement of gaseous combustion products from the combustion cylinder during the latter part of such compressing stroke.
10. In combination, an internal combustion engine and means for starting the same comprising a combustion cylinder directly connected to the internal combustion engine to supply fluid thereto under high pressure and without substantial loss of heat, means for supplying fuel and medium capable of supporting combustion to said combustion cylinder, a displacement member reciprocable in said combustion cylinder, actuating means therefor driven independently of the power generated by such combustion within said cylinder, and means for timing the burning of said mixture and the discharge of the gaseous products of combustion from said cylinder so as to cause said piston to displace said combustion gases during a portion of the compressing stroke and under the pressure generated by such combustion.
11. In combination, an internal combustion engine permanently connected to its load, and means for supplying gaseous combustion products at high temperature and under high pressure to said engine to start the same under its load comprising a combustion chamber, means for supplying fuel and medium capable of supporting combustion to said combustion chamber,

a displacement member reciprocable in said combustion chamber, means for delivering gaseous products of combustion directly from said chamber to said engine, valve mechanism controlling such discharge, a prime mover for moving said displacement member against the pressure generated by such combustion in said combustion chamber, and timing means controlling the burning of said mixture and the operation of said valve mechanism to cause displacement of gaseous combustion products from said combustion chamber into said engine during the latter part of the compressing stroke of said displacement member.

12. In combination, an internal combustion engine having a combustion chamber and a piston reciprocable therein, means for burning a mixture of fuel and a combustion supporting medium and supplying gaseous products of combustion to said combustion chamber for starting said engine, said starting means comprising power driven mechanism for pumping said products of combustion into said combustion chamber, and means for controlling the delivery of said products of combustion to said combustion chamber in timed relation to the reciprocation of said piston.

13. In combination, an internal combustion engine having a combustion chamber and a piston reciprocable therein, means for burning a mixture of fuel and a combustion supporting medium and supplying the gaseous products of combustion to said chamber for starting said engine, said starting means comprising mechanism for pumping said products of combustion into said chamber, a motor for actuating said pumping mechanism, and means for controlling said starting means so as to interrupt the supply of products of combustion to said chamber during movement of said piston in said chamber in one direction.

14. In combination, an internal combustion engine having a combustion chamber and a piston reciprocable therein, means for burning a mixture of fuel and a combustion supporting medium and supplying the gaseous products of combustion to said chamber for starting said engine, said starting means comprising a motor-driven pump for pumping said products of combustion into said chamber, and means controlled by the reciprocation of the piston of said engine for interrupting the burning of the fuel during movement of said piston in said chamber in one direction.

15. In combination, an internal combustion engine having a plurality of combustion chambers and pistons reciprocable therein, means for burning a mixture of fuel and a combustion supporting medium for starting said engine, said starting means comprising mechanism for pumping said products of combustion into said chambers, a motor for actuating said pumping mechanism, and means controlling said starting means so as to supply products of combustion to an engine chamber only during movement of its respective piston away from the head end thereon.

16. In combination, an internal combustion engine having a plurality of combustion chambers and pistons reciprocable therein, and starting means for said engine comprising a motor, a reciprocating pump driven thereby, means for supplying to the pumping chamber of said pump a combustion supporting medium and fuel and burning the mixture during the compression stroke of said pump, means for conducting the

gaseous products of combustion from said pumping chamber to the combustion chambers of said engine, and means for controlling the delivery of combustion products to each chamber in timed relation to the reciprocation of the respective piston therein.

17. In combination, an internal combustion engine having a combustion chamber and a piston reciprocable therein, and means for supplying hot gaseous combustion products to the combustion chamber thereof under pressure for starting said engine, said means comprising a chamber for burning a mixture of a combustion supporting medium and fuel, a displacing member reciprocable in said last mentioned chamber and power driven means for actuating said displacing member to pump the hot gaseous combustion products into the combustion chamber of said engine, a valve for controlling such supplying of gaseous combustion products to said engine combustion chamber, and timing means for timing the actu-

ation of said valve in synchronism with the reciprocation of said piston.

18. In combination, an internal combustion engine having a plurality of combustion chambers and pistons reciprocable therein, and means for supplying hot gaseous combustion products to said chambers under pressure for starting said engine, said means comprising a chamber for burning a mixture of a combustion supporting medium and fuel, a displacing member reciprocable in said last mentioned chamber and power driven means for actuating said displacing member to pump the hot gaseous combustion products into the combustion chambers of said engine, means for conducting said combustion products from said pumping chamber to the combustion chambers of said engine, valves for controlling said conducting means, and timing means for timing the actuation of said valves in synchronism with the reciprocations of the respective pistons.

FREDERICK F. MURRAY.

CERTIFICATE OF CORRECTION.

Patent No. 1,995,320.

March 26, 1935.

FREDERICK F. MURRAY.

It is hereby certified that error appears in the printed specification of the above numbered patent requiring correction as follows: Page 4, second column, line 46, for ", 11 and 14" read and 11; and line 48, for "and 11" read , 11 and 14; and that the said Letters Patent should be read with these corrections therein that the same may conform to the record of the case in the Patent Office.

Signed and sealed this 28th day of May, A. D. 1935.

Leslie Frazer

(Seal)

Acting Commissioner of Patents.
